F. CHILDS

SELF INKING HAND STAMP

Filed May 13, 1924

Inventor
FREDERICK CHILDS

Attnorneys.

Patented July 28, 1925.

UNITED STATES PATENT OFFICE.

FREDERICK CHILDS, OF SAN FRANCISCO, CALIFORNIA.

SELF-INKING HAND STAMP.

Application filed May 13, 1924. Serial No. 713,060.

To all whom it may concern:

Be it known that I, FREDERICK CHILDS, a citizen of the Dominion of Canada, and a resident of San Francisco, county of San Francisco, State of California, have invented a new and useful Self-Inking Hand Stamp, of which the following is a specification.

The present invention relates to improvements in self-inking hand stamps and has particular reference to hand stamps now commonly used in which a plurality of ribbons having characters molded thereon are mounted in parallel relation so as to pass over the bottom of a supporting structure and to present characters in a desired order at the bottom face for stamping purposes.

The principal object of the present invention is to provide in connection with a hand stamp of such simple construction an inking pad that will automatically resume its place opposite the bottom face and that may be readily removed by a slight pressure on an element projecting from the handle when it is desired to use the device. Further objects and advantages of my invention will appear as the specification proceeds.

The preferred form of the invention is illustrated in the accompanying drawing, in which Figure 1 shows a front view of my improved stamp, Figure 2 a vertical section through the same taken along line II-II of Figure 1, and Figure 3 a similar section showing my inking pad swung sideways so as to clear the bottom face of the stamp. While I have shown only the preferred form of the invention, I wish to have it understood that various changes or modifications may be made within the scope of the claims hereto attached without departing from the spirit of the invention.

The stamping device shown in the drawing is substantially of conventional construction and includes two side plates (1) connected by a top element (2) and a bottom element (3) in such a manner as to present a substantially rectangular retainer for the working mechanism of the stamp, the side elements being preferably tapered so as to narrow down toward the bottom to a width corresponding to the height of the characters to be used.

Mounted in the upper portion of the frame is a shaft (4) on which are rotatably disposed a plurality of drums (6) having

flanges (7) thereon by means of which they may be manipulated. Endless ribbons (8) pass over the drums and the bottom plate (3) in parallel relation to one another and have various characters printed or molded thereon so that various combinations of characters may be assembled at the bottom face. A handle (9) extends upwardly from the top plate (2). No novelty is claimed for the device thus far described.

An inking pad (11) made to fit the bottom face of the exposed ribbons is provided with arms (12) extending from the ends thereof which straddle the sides of the frame and are pivoted to the same as shown at (13) near the edges thereof. The arms, which are substantially of the same width as the sides of the frame, are formed with slanting slots (14) near the upper edges thereof.

A yoke (16) mounted for vertical reciprocating motion has pins (17) extending from the extremities thereof which pins are adapted to ride in slots (14). The connecting member (18) of the yoke rides in vertical slots (19) in the sides and has extending upwardly therefrom, slightly offset, the rod (21) extending through the handle (9) and formed integral with a cap (22) which latter is also slidable in a vertical perforation (23) in the handle (9).

A spring (24) disposed between the cap (22) and the top face (2) of the frame tends to project the cap upwardly and to thereby swing the pad (11) into an operative position relative to the bottom characters.

The device is manipulated as follows:

Ordinarily it will lie on the desk ready for use with the inking pad in an operative position. When it is to be used the operator lifts it from the desk, depresses the cap (22) and applies the stamp. The depressing of the cap (22) forces the yoke (16) downwardly over the opposition of the spring (24) and causes the pins (17) to ride in the slots (14) while simultaneously swinging the arms (12) about the pivot (13). The pad is thus temporarily made to clear the bottom face of the stamp until the stamp has been used, whereupon the operator may just place it back on the desk, when the spring will automatically return the pad to its operative position.

I claim:

1. In a hand stamp of the character described, a substantially rectangular frame,

a shaft mounted parallel to the bottom thereof, drums mounted on the shaft, endless ribbons encircling the drums and the bottom element of the frame having characters thereon adapted to be presented downwardly in selected combinations, an inking pad pivoted to the frame and adapted to be selectively swung into an active and an inactive position relative to the downwardly presented characters, a push button in the top of the handle and an operative connection between the push button and the inking pad allowing the latter to be operated by the former.

15 2. In a hand stamp of the character described, a substantially rectangular frame, a shaft mounted parallel to the bottom thereof, drums mounted on the shaft, endless rib-

bons encircling the drums and the bottom element of the frame having characters 20 thereon adapted to be presented downwardly in selected combinations, an inking pad adapted for engagement with the downwardly presented characters having arms extending therefrom adapted to straddle the side 25 elements of the frame and pivoted thereto near one edge thereof, a push button in the top of the handle and a set of rods operatively associated therewith having pins extending therefrom riding in slanting slots 30 in the arms for swinging the same about their pivots when the push button is depressed so as to swing the inking pad into an inactive position.

FREDERICK CHILDS.
